UNITED STATES PATENT OFFICE

JAMES McDONALD, OF WEEHAWKEN, NEW YORK, ASSIGNOR TO TODD DRY DOCK, ENGINEERING & REPAIR CORPORATION, OF BROOKLYN, NEW YORK

APPARATUS FOR LIQUID AND PULVERIZED FUEL FURNACES

Application filed June 17, 1929. Serial No. 371,400.

This invention relates to apparatus for use with furnaces employing liquid or pulverized fuel as the combustible medium and wherein means are provided for admitting 5 regulated quantities of air to support combustion.

My present improvements are directed to means, equally applicable with liquid or pulverized fuel burning apparatus adapted for 10 either natural draft or forced draft, said means being intended to cause a sufficient volume of air to be introduced into the flame nearer the point of fuel issuance from the burner nozzle than has heretofore been attainable in liquid fuel burning furnaces, with 15 the object of securing more complete combustion of the fuel. Also my improvements have the effect of preventing the air that flows through the flame cone slots from spreading 20 away from the flame, and tending to restrict its radial dispersion, thereby causing this air supply to be directed into the main combustion zone.

Other features and advantages of my invention will hereinafter appear.

In the drawings:

Figure 1 is a central sectional view of a burner apparatus, of the Todd natural draft type, including my improvements.

Fig. 2 is a rear view of my improved flame cone, on an enlarged scale.

Fig. 3 is a front view of said flame cone, and

Fig. 4 is a section on the line 4—4 of Fig. 3. While for the purpose of describing my improvements I have in this application shown them as applied to a Todd type furnace front adapted to supply air under natural draft to a furnace, it is to be understood 40 that my improvements are equally applicable to other apparatus, either for natural or forced draft, and are therefore not limited by or to the apparatus shown herein.

In Fig. 1 there appears a furnace front 45 having the casing 1 which is provided with means of connection to the furnace plate 2, and has an opening in the form of a Venturi ring 3, directed toward the furnace interior, and the brick venturi 4. Included within the 50 furnace front is the jacket tube 5, the burner

tube 6 therein, and the atomizing nozzle 7. The air cone 8 co-acts with the Venturi ring 3 to regulate the amount of air supplied to the furnace.

The parts thus described and others shown 55 in Fig. 1 correspond with the disclosure in U. S. Patent No. 1,412,023 and need no further elaboration herein.

The present improvements relate to the structure of the flame cone, here generally 60 designated by the numeral 9, which is mounted on the jacket tube 5, near the inner end thereof, and is provided with rods 10 whereby it may be adjusted longitudinally. Said flame cone is here shown as provided with 65 an encircling ring or annulus 11, having the forward portion 12 and rearward portion 13. Also the flame cone 9 is perforated with a series of tangential slots 14 that extend therethrough, from front to rear, for the purpose 70 of giving a whirling motion to air introduced thereby into the furnace.

It is the novel characteristic features of 75 this flame cone which constitute my present improvements.

The forward flange portion 12 of the flame cone serves to confine the quota of air flowing over the cone toward the furnace entrance, thereby restraining its tendency to enter the furnace, away from the flame, in an enlarging 80 conoidal formation, but instead causing this quota of air to pass through the slots 14 to thus mingle with the liquid fuel issuing from the nozzle at the genesis of flame propagation, in this manner assuring more complete combustion than is otherwise possible.

By reason of the tangential arrangement 85 of slots 14 air passing therethrough is given a whirling motion that causes it to blend or mix with the fuel, but since this whirling motion tends to spread the air flow away from the proper confines of the flame zone I have provided the rearward annulus portion 13 to restrict this outward flare of the air flow, said portion 13 having the effect of straightening 90 out the whirling air currents, and confining them in the rearwardly directed cylindrical path of the flame.

Since the slots 14 are formed obliquely 95 through the material of flame cone 9, as 100

shown in Fig. 4, the streams of air flowing therethrough in whirling formation, pass contactingly against the rearward surface of said flame cone and exert a cooling influence thereon, thereby prolonging its life.

It is to be understood that while the specific description of the herein given apparatus or furnace front is directed to a type of apparatus having a burner particularly adapted for the employment of liquid fuel, the flame cone constituting my present improvement is equally useful in conjunction with apparatus having a burner adapted for employment with pulverized coal.

Variations within the spirit and scope of my invention are equally comprehended by the foregoing disclosure.

I claim:

1. The combination with a furnace having a fuel burner, air supply means and a flame cone surrounding said burner, said cone provided with tangential slots for the passage of air, of a cylindrical annulus surrounding said cone to present a forward flange adapted to direct air flow toward said slots and a rearward flange to restrict the radial dispersion of the air streams at the rear of the cone.

2. The combination with a furnace having a fuel burner, air supply means and a slotted flame cone surrounding said burner, of a forwardly directed cylindrical flange surrounding said flame cone and extending from the area adjacent one extremity of the slots in said cone to confiningly direct air flow toward said slots.

3. The combination with a furnace having a fuel burner, air supply means and a flame cone surrounding said burner, said cone provided with tangential slots for the passage of air, of a rearwardly directed cylindrical flange surrounding said cone, to restrict the radial dispersion of the air streams at the rear of the cone.

Executed this 12th day of June, 1929.
45 JAMES McDONALD.
